DATA RECORDER UNIT

Gunther W. Newman, Old Route 28, Phoenicia, N.Y.
12464, and William A. Seabury III, Highland Road,
Ulster Park, N.Y. 12487

Filed Jan. 7, 1969, Ser. No. 15,244

Term of patent 14 years

Int. Cl. D14—02

U.S. Cl. D26—5

FIG. 1 is a top plan view of a data recorder unit showing our new design;

FIG. 2 is a side elevational view looking from the right side of FIG. 1 thereof;

FIG. 3 is a side elevational view looking from the left side of FIG. 1 thereof;

FIG. 4 is a bottom plan view thereof;

FIG. 5 is a front elevational view thereof; and

FIG. 6 is a rear elevational view thereof.

We claim:

An ornamental design for a data recorder unit, substantially as shown.
